England, assignors to Celanese Corporation of
America, a corporation of Delaware

Application March 26, 1941, Serial No. 385,230
In Great Britain April 3, 1940

18 Claims. (Cl. 8—146)

This invention relates to the stretching of textile filaments or threads and in particular to the stretching of textile filaments or threads in a softening medium for such purposes as increasing their strength. The invention is especially concerned with operations in which the softening medium employed is a gaseous medium, such as steam, under pressure.

U. S. application S. No. 372,108 filed December 28, 1940, describes such an operation in which the initiation of the stretching is brought about by feeding the material to be stretched into a stretching chamber at a fixed input speed and withdrawing it from the stretching chamber at a speed which is initially equal to the input speed, but steadily increases in accordance with the amount of softening effected, the tension in the material being used to control the outlet speed of the material until the required rate of stretch has been reached, e. g. up to 5, 10, 20 or more times the original length of the threads. It is an object of the present invention to enable the initial input speed to be reduced, as well as the output speed, and, besides increasing the output speed from equality with the input speed until the desired speed ratio between input and output has been attained, to speed up the operation as a whole from a low starting speed to the desired production speed.

According to the present invention, in the stretching of textile materials in the form of filaments or threads while they are running through a gaseous softening medium under pressure, the material is caused to run through the softening medium with an output-input speed ratio equal to the degree of stretch required, and the input and output speeds are then varied while maintaining said ratio substantially constant and the pressure of the gaseous medium is simultaneously varied under the control of the tension in the material as it leaves said softening medium so that, as the tension varies with the change in speed, the softening effect of said medium is varied in a corresponding manner. In this way, stretching may be started at a low overall speed, which is then increased to full production speed. Similarly, the operation may be stopped in an inverse manner.

The control of the pressure may conveniently be effected in accordance with the tension in the material being stretched by the provision of a device sensitive to tension, such as a rod mounted on a lightly spring- or weight-loaded arm, round which rod the material emerging from the stretching operation is caused to turn

through an angle, and a relay for amplifying the small and delicate force exerted by the tension in the material on the rod into a powerful force by which a valve determining the pressure may be controlled. For example, the motion of the arms carrying the rod may actuate a needle valve controlling the supply of compressed air to a spring-loaded diaphragm, to which is secured a connecting rod giving a powerful thrust derived from the pressure of the air over the large area of diaphragm.

According to a further feature of the invention a tension-sensitive device and relay of the kind described above may be employed for other purposes. In particular they may be used for controlling also the speed of take-up packages on which the stretched materials are collected, which packages, as they increase in size need to be rotated more slowly in order to take up the material at a constant linear rate. This may be done by causing the relay to control an infinitely variable gear-box driving the packages, and indeed the device may be applied to all cases where delicate control of tension is desired and where infinitely variable gears or like regulators are in use.

The increase in speed, together with a corresponding increase in pressure in accordance with the invention, may conveniently be carried out after the desired ratio between the input speed of the material and the output speed has been attained by suitable means, e. g. by the means described in U. S. application S. No. 372,108 referred to above, or by the use of an additional tension-sensitive device, relay, and variable gear.

The invention may be employed in conjunction with the invention described in U. S. application S. No. 375,420 filed January 22, 1941, in which material to be stretched is supplied to a stretching chamber containing a softening medium under pressure from a feed chamber which contains a medium under pressure but a lower pressure than that of the softening medium in the stretching chamber. According to U. S. application S. No. 375,420, means are provided whereby the pressure in one of these two chambers, preferably the feed chamber, is controlled in accordance with the pressure in the other so as to maintain the desired difference in pressure between the chambers, and further an automatic control is provided for the one pressure medium so that this medium is automatically brought to and held at the desired working pressure. The pressure-controlling

devices by which these effects are brought about for the purposes of the prior specification may well be adapted for the purposes of the present invention. Thus, the means by which the pressure is held at a desired amount may be placed under the control of the tension-sensitive device referred to above so that the desired amount, constituting the upper limit of the pressure under the control of the device, may itself be steadily increased under the control of the tension in the materials being stretched. In this way, when the tension increases as a result of an increase in the rate of travel of the material, the pressure in the stretching chamber may be increased, so that the rate of softening of the material is increased to correspond with the increased rate of travel.

By way of example one arrangement of apparatus suitable for carrying out the present invention, and incorporating the device described in U. S. applications S. No. 372,108 and S. No. 375,420 mentioned above, will now be described in greater detail with reference to the accompanying drawings in which:—

Figure 1 is a diagrammatic side view of the apparatus as a whole;

Figure 2 is a diagrammatic plan view of part of Figure 1;

Figures 3 and 4 are a side elevation and plan view respectively of a tension-sensitive device employed for the purpose of the invention;

Figure 5 is a sectional elevation of a mechanical control means under the pneumatic control of the device shown in Figures 3 and 4, and

Figures 6 is a diagrammatic side view of a modification of the apparatus as a whole.

In the apparatus shown in Figure 1 a number of threads 1 are taken from bobbins 2 mounted in a creel 3, are led through guide-eyes 4 in connection with the creel 3 and proceed from the guide-eyes 4 to a spacing comb 5. From the comb 5 the threads 1 enter a stretching apparatus of the general form described in U. S. Patent No. 2,053,278. This comprises a feed chamber 6 having apertures 7 through which the threads enter and containing nip-rollers 8 by means of which the rate at which the threads are drawn into the stretching apparatus is accurately controlled. From the feed chamber 6 the threads 1 pass to a stretching chamber 9, entering through apertures 10 and leaving through apertures 11. During the stretching operation the stretching chamber 9 is supplied through a pipe 12 with moist steam under pressure and the feed chamber 6 is supplied with compressed air through a pipe 13. The compressed air in the chamber 6 is supplied at a pressure slightly lower than that of the steam in the chamber 9 and minimises the flow of steam from the chamber 9 through the apertures 10, so that the threads, softened in the chamber 9, are not broken by being blown back into the chamber 6.

During the initiation of the stretching operation the supply of both steam and air through the pipes 12 and 13 respectively is at first shut off, so that the threads 1 may be led through the chambers 6 and 9. The threads emerging from the apertures 11 are gathered as a rope, which passes round a fixed guide pulley 14, round which it turns at an angle of approximately 90°, and proceeds to a guide pulley 15 mounted on a vertical axis on a compensator bar 16 pivoted at 17 and carrying a further pulley 18 on a horizontal axis at its other end. A spiral spring 19 urges the compensator bar 16 in a counter-clock-

wise direction from above, and the pull of the threads 1 between the pulleys 14 and 15 initially counteracts the pressure of the spring 19. The compensator bar 16, with its pulleys 15 and 18 and spring 19 together constitute the tension-sensitive means described and claimed in U. S. application S. No. 372,108. On their way to the fixed guide pulley 14 the threads pass (but do not at first engage with) a tension-sensitive device, indicated generally in Figures 1 and 2 at 20, and described in greater detail with reference to Figures 3 and 4. While the threads are engaged with the members 14—19, as shown in Figure 1 and in dotted lines in Figure 2, they pass beneath the device 20; they are not threaded up through the device 20 as shown in full in Figure 2 until, at a later stage, they are disconnected from the members 14—19.

The pulley 18 guides the rope of threads 1 to 20 a conical roller made up of three parts 21, 22 and 23, the parts 21 and 23 being cylindrical and having diameters proportional respectively to the unstretched length of the threads and the stretched length desired. The part 22 is the conical part, and connects the parts 21 and 23. The length of the part 22 and the position of the point 17 are arranged so that the pulley 18 is always close to one or other of the parts 21, 22, 23, and guides the threads 1 passing over it accurately to the conical roller, to the under side of which the threads pass.

Co-operating with the large part 23 of the conical roller is a further roller 24 constituting, with the roller 23, a pair of nip-rollers similar to the rollers 8 in the chamber 6. Beyond the rollers 23 and 24 the threads encounter a comb 25, a set of three drying drums 26, a further comb 27, a pair of mangle rollers 28 and a take-up creel for the collection of the stretched threads. The comb 27 and the mangle rollers 28 are wider than the nip-rollers 8 and 24, being of a size appropriate to the width of the take-up creel, the creel comprising a waste swift 29 and take-up bobbins 31.

The steam is fed by the pipe 12 to the stretching chamber 9 through a steam valve 32 under the control of pressure-sensitive pressure controller, indicated generally at 33, operated by compressed air. The steam valve 32 is adjusted, to maintain a desired steam pressure in the steam chamber 9, by means of a spring-loaded diaphragm 34 subjected on one side to an air pressure supplied through the pipe 30 by the controller 33. For a full understanding of the invention in the particular application of it here described, it is desirable to refer in some detail to the manner in which the controller acts and the functions which, directly or indirectly, it performs.

Air is supplied to the controller 33 at a pressure of 17 pounds per square inch from the air supply main 13 and valves 35, 36 through a branch pipe 37 and a suitable reducing valve 38. The air so supplied is able to pass through one valve 39 into a pipe 40 communicating with the diaphragm 34 of the steam valve, and is able to pass from the pipe 40 through another valve 41 controlling a leak 42, whereby the air may escape into the atmosphere. The two valves 39, 41 controlling the air in this manner are coupled together by a member 43, so that as one opens the other is closed, and by these means the air pressure applied to the diaphragm 34 of the steam-controlling valve 32 is varied. Thus, by opening the valve 39 by which the air reaches the diaphragm 34 and by closing the valve 41 by which the air escapes through the leak 42, the pressure applied

to the diaphragm 34 may be increased to any degree up to a limit of 17 pounds per square inch, while by closing the valve 39 and opening the valve 41, the pressure applied to the diaphragm 34 may be reduced, if necessary to atmospheric pressure. The position of the coupled valves 39, 41 controlling the air is determined by the air pressure in a bellows 44, the bellows being in communication with an air line 45 through which air from the supply at 17 pounds per square inch, after passing through a suitable fixed throttling device 50, escapes by a controlled leak to the atmosphere. The controlled leak is in the form of a nozzle 51 from which the exit of the air is opposed by a pivoted flapper 52. The flapper 52 is connected by a lever and link 46, 47 to a pressure sensitive element 53, in the form of a Bourdon tube subjected through a pipe 54 to the pressure in the steam chamber 9, i. e. the pressure it is desired to control. When the pressure in the steam chamber 9 is high, the flapper 52 is pivoted closer to the nozzle 51, so increasing the pressure in the air line 45 behind the nozzle, and when the steam pressure is low the flapper 52 is pivoted away from the nozzle 51 and reduces the pressure behind the nozzle. Accordingly, the pressure in the bellows 44 in communication with the air line 45 is made to depend upon the pressure in the steam chamber 9, a high pressure in the steam chamber 9 increasing the pressure in the bellows 44, while a low pressure decreases the pressure in the bellows. The expansion of the bellows 44, and the consequent movement to the left of the member 43 are arranged to close the valve 39 admitting air to the steam valve diaphragm 34 and to open the valve 41 by which air escapes through the leak 42, and the resulting drop in the pressure applied to the diaphragm 34 closes the steam valve 32 and reduces the steam pressure. By these means, the pressure in the steam chamber 9 is maintained at the desired level. A pen 55 is secured to the flapper 52, so as to record on a chart 56 the pressure in the steam chamber 9 as communicated to the pressure sensitive element 53 controlling position of the flapper 52 about its axis, 57.

In order to reduce the sensitivity of the controller 33, so as to avoid hunting, the air escaping from the nozzle 51 is caused to pass through an elastic bellows 62 adapted to absorb any violent fluctuations of pressure behind the nozzle. For the same purpose, a leak 63 is provided in the air line 45 immediately before the elastic bellows 62. The leak 63 is controlled by a valve 64, which may be adjusted so as to adjust the sensitivity of the controller 33 and is coupled with a throttling valve 65 in the air line 45. The two valves 64, 65 are adjusted together by hand. When the leak 63 is shut and the throttling valve 65 full open, the sensitivity is greatest. By slightly opening the leak 63 without much affecting the throttling valve 65 the sensitivity may be reduced. By widely opening the leak 63 and nearly closing the throttling valve 65, the leak at the nozzle 51 is rendered ineffective, and the steam valve 32 may then be controlled by hand, by manipulating the reducing valve 38 through which air is supplied to the controller 33.

As an additional precaution against hunting, means are provided whereby relative movements between the nozzle 51 and the flapper 52 are damped, any movement of the flapper 52 being at first accompanied by a corresponding movement of the nozzle 51, the nozzle returning after a time to its original position. For this purpose

the nozzle 51 is pivoted about the same axis 57 as the flapper 52.

The nozzle 51 is connected by means of a lever 59 and a link 66 to one arm 67 of a bell-crank lever, which is pivoted at 68 on another lever 69, which, for the purposes of the mechanism here described, may be regarded as stationary. The other arm 70 of the bell-crank lever is connected by a frame 71 and link 72 to a point 73 between two elastic bellows 74, 75, both of which communicate with the space behind the diaphragm 34 of the steam valve 32. One of these bellows 74, communicates directly with this space and the other, 75, through a substantial capillary resistance 76. Thus, any change in pressure behind the diaphragm 34 is immediately communicated to the bellows 74, so that the point of connection 73 between the bellows 74, 75 is moved and consequently through the bell-crank lever 67, 70 and the link 66, the nozzle 51 is moved. After a time lag, depending on the magnitude of the capillary resistance 76, the same pressure is communicated to the other bellows 75 which acts against the bellows 74 and restores the nozzle 51 to its original position.

The compressed air for the feed chamber 6 is supplied in the manner described and claimed in U. S. application S. No. 375,420. The compressed air, coming from the main 13 through the valves 35, 36 reaches the feed chamber 6 through an air supply valve 77 actuated by a spring loaded diaphragm 78, one side of which is exposed to the pressure of the steam in the stretching chamber through a pipe 79 branching off the pipe 54. The other side of the diaphragm 78 is subjected to an air pressure existing between a pair of coupled valves 80, 81 through which, in series, air supplied from the air main 13 escapes by a leak 82. The coupled valves 80, 81, together constituting a setting valve, are actuated by a diaphragm 83, loaded by a spring 84 whose pressure is adjustable by means of a screw 85, and exposed on one side, through a pipe 86, to the air pressure in the feed chamber 6, and on the other, through a pipe 89, to the pressure between the coupled valves 80, 81. By adjusting the spring 84 co-operating with the setting valve diaphragm 83, the difference in pressure maintained on the two sides of the diaphragm 83 may be adjusted to any constant amount, for, unless the pressure difference balances the force of the spring 84, the diaphragm 83 will be distorted, and the setting valve position altered until balance is obtained. In this way the air supplied to the feed chamber 16 through the air supply valve 77 is under the control of a diaphragm 78, which is exposed on one side to the steam pressure and on the other to a pressure differing by a constant amount from the pressure in the feed chamber 6. Thus, any change in the steam pressure is communicated to the valve 77 controlling the air supplied to the feed chamber 6 and produces a corresponding change of air pressure in the feed chamber 6. The valves 32, 37, 80 and 81 are more fully described in U. S. application S. No. 375,420.

In order to adjust the desired pressure in the steam chamber 9, (and consequently also the air pressure in the chamber 6) the nozzle 51, which co-operates with the flapper 52 may be adjusted about its pivot 57 independently of the movement given to it by the bellows 74, 75 as described above. For this purpose the lever 69, on the point 68 of which the bell crank lever 67, 70 is pivoted, is connected by means of link 90

and lever 69 to a worm wheel 92 actuated by means of a worm 93 on a spindle 94 extending outside the controller 33. The lever 69 pivots about a fixed axis in line with the mean position of the axis about which the lever 72 pivots, so that when the spindle 94 is rotated the nozzle 51 is pivoted about its axis 57 without substantially disturbing the relative positions of the levers 67, 69, 70 and 72. A pointer 95 is provided, connected to the upper end of the lever 69 by means of lever 96 and link 97, the pointer 95 indicating against the chart 56 the pressure that the controller 33 is set to give by means of the spindle 94.

The spindle 94 is provided with a knob 98 for hand setting, but carries in addition a small pinion 99 engaging with a larger pinion 100 by means of which it may be automatically set. For the purpose of the present invention the spindle 94 is controlled through pinions 99, 100 by the tension sensitive device 20 in the following manner.

The tension sensitive device 20 comprises, as shown in Figures 3 and 4, a fixed guide bar 101 and two movable guide bars 102, 103 connected by a bar 104 to form a frame, which is pivoted in ball bearings 105 disposed at the axis of the bar 103. A block 106 to which the bars 102, 103, 104 are connected carries two screws 107 on which weights 108 are adjustably mounted so that the whole assembly 102-108 may be brought out of balance, tending, in Figure 3, to rotate in a clockwise direction. The threads 1 pass under the bars 101, 103 and over the bar 102 so that the tension in them prevents the rotation of the bars 102, 103 under the out-of-balance forces due to the weights 108. Fixed beneath the block 106 is a needle valve 109, the spring loaded needle 110 of which is provided at its upper end with a spherical bearing surface 111 engaging with the under side of the block 106. Compressed air is supplied to the needle valve 109 through pipe 112 and leaves it through the pipe 113. A screw 114 on an extension 115 of the needle valve 109 limits the upper position of the valve needle 110. By these means the position of the needle 110 is regulated in accordance with the tension in the threads 1 passing under the bars 101, 103 and over the bar 102, a higher degree of tension in the threads 1 opening the valve 109 and a lower degree allowing the valve to be closed under the influence of the adjustable weights 108.

As shown in Figure 1 the pipe 112 branches off the pipe 31 supplying the controller 33 with compressed air, a reducing valve 116 being included in the pipe 112 to reduce the pressure of the air, which is supplied by the valve 38 at 17 lbs. per square inch, to a pressure of about 1½ lbs. per square inch. The pipe 113 leaving the valve 109 leads to a spring loaded diaphragm 117 shown in greater detail in Figure 5. The diaphragm 117 is enclosed on one side by a casing 118, and air behind the diaphragm 117 may escape from the casing 118 by means of a leak 119. The leak 119 is a fixed leak, in the form of a nozzle offering a resistance to the escape of air. If desired, however, the leak may be in the form of a valve close to the valve 109, and coupled therewith to operate in the same manner but in the opposite sense, like the valves 39 and 41. In either case, the pressure behind the diaphragm 117 is regulated in accordance with the degree to which the needle valve 109 is open, and therefore in accordance with the tension in the threads. The diaphragm 117 is loaded by means of a spring 120 acting on a rod 121 secured at

one end to the diaphragm, the other end of the rod 121 extending into a sleeve 122 to which it may be secured, when required, by means of a thumb screw 123. The sleeve 122 terminates in a rod 124 connected to a crank pin 125 extending from the side of the large pinion 100. By these means the spindle 94, controlling the pressure to which the controller 33 is set, may be regulated by changes in the tension of the threads 1 leaving the chamber 9.

The valves 35, 36 in the main air supply 13 are, respectively, a reducing valve, for bringing the air supply down to a convenient pressure of about 60 lbs. per square inch, and a stop valve for the purpose of closing down. A reducing valve 87, and a stop valve 88 are provided in the main steam supply 12 for similar purposes. The reducing valves 35, 36 and 87 are adjusted, and the stop valve 31 opened before the apparatus is started up, the air still being under the control of the air supply valve 77, which is shut.

In starting up the device the threads 1 are drawn from the bobbins 2 and threaded through the comb 5 and through the chambers 6 and 9, being collected in the form of a rope at the pulley 14 and proceeding as a rope round the pulleys 15 and 18 and on to the small end 21 of the conical roller. The nip-rollers 8 and the conical roller are then driven at such a speed that the peripheral speed of the nip rollers 8 is equal to that of the small part 21 of the conical roller. A common drive to the nip rollers 8 and conical roller is employed so that their relative angular speeds are positively fixed, the common drive being effected through a P. I. V. gear (not shown), and being initially slower than is ultimately required.

The steam stop valve 81 is then opened and the pressure sensitive pressure controller 33, being disconnected by loosening the thumb screw 123 and set to give an appropriate pressure, allows the steam valve 32 to admit steam to the steam chamber 9, and at the same time the interconnection 54, 79 between the steam chamber 9 and the air valve 77 for the feed chamber 6 admits air to the latter at a lower pressure, determined by the strength of the spring in the air supply valve 77, and the adjustable spring 84. The steam pressure rapidly builds up, the air pressure following with the predetermined difference until full pressure is reached in both chambers, at which time the controller 33 operates to keep the two pressures steady and at the required difference. During this short interval of time, the conical roller 21, 22, 23 draws the increasingly softened threads, in the manner described in U. S. application S. No. 372,108, at a faster and faster rate until the full degree of stretch is reached, although as yet the over-all speed of the whole apparatus is much below what is ultimately required for production purposes. Then, as in that specification, the threads 1 are unhooked from the pulleys 14, 15 and 18, cut on the roller 23 and led over the comb 25 round the drying drums 26, over the comb 27, through the mangle rollers 28 and so to the waste swift 29. They may then be separated in the dents of the reed 25, so that they run as a sheet, picked off one by one from the swift 29, and led through the appropriate dents of the reed 27 to the take-up packages 31.

This completes the bringing of the apparatus to full stretch in the manner described in U. S. applications S. Nos. 372,108 and 375,420. The threads 1 have been disconnected from the device 14-19 and are running as a sheet directly from

the apertures 11 in the chamber 9 to the drawing rollers 23, 24 as shown in Figure 2.

The threads are then engaged with the tension sensitive device 20, by threading them over the movable bar 102 thereof, and at the same time the thumb screw 123 is tightened, connecting the rod 121 to the sleeve 122. The speed of the rollers 8 and the rollers 23, 24 is then steadily increased by means of the P. I. V. gear in their common drive, without affecting the rates of their speeds or the degree of stretch effected by them on the threads 1. As a result of the increasing speed with which the threads are drawn through the apparatus, the time during which they are in the chamber 9 and under the influence of the steam is decreased. In consequence, they are softened to a smaller degree, and a greater tension is necessary to bring about the degree of stretch determined by the fixed relationship between the speeds of the rollers 8 and the rollers 23, 24. This increase of tension acts upon the movable bar 102, rotating the block 106 in an anti-clockwise direction (Figure 3) whereby the needle valve 109 is caused to open. The opening of the needle valve 109 permits a flow of air through the pipes 112, 113 to the chamber 118 enclosing the diaphragm 117. Except for a small amount necessary to increase the volume of the space behind the diaphragm 117, the extra air all escapes through the leak 119, but the increased rate of flow from the leak 119 requires a higher pressure, which is communicated to the diaphragm 117. The diaphragm 117 moves, under this pressure, against the action of the spring 120 and carries with it the rod 121, and sleeve 122 connected thereto by the thumb screw 123. This rotates the large pinion 100 through the rod 124 and the crank pin 125 and consequently rotates the small pinion 99 and the spindle 94. The rotation of the spindle 94 pivots the nozzle 51 and causes the controller 33 to permit a higher pressure in the chamber 9. The air pressure in the chamber 6 continues to follow the increasing steam pressure in the chamber 9. This process continues until the rollers 8 and the rollers 23, 24 are being driven at full production speed, and in practice the change takes only a few seconds. These few seconds, however constitute a very critical period in the starting of the operation, during which, to avoid breakdown, the pressure of the steam and consequently the temperature and the intensity of the softening effect must be closely controlled in accordance with the overall speed of the operation. This close control is made possible by the present invention. When full production speed is reached, the needle valve 109 is brought up against the stop 114 and the spindle 94 is brought to a corresponding position. At this stage the thumb screw 123 may again be disconnected and the threads may if desired be unthreaded from the tension sensitive device 20.

Termination of the stretching operation may be effected by reversing the operations described above. First, the threads being threaded in the device 20, the thumb screw 123 is tightened. Then the common drive to the rollers 8 and the rollers 23, 24 is steadily and rapidly slowed down, the increasing softness of the threads due to their greater period in the chamber 11 causing the valve 109 to close and so permitting the chamber 118 to be deflated through the leak 119. This rotates the pinion 100 and the spindle 94 and reduces the pressure that the controller 33 is set to give in the chamber 9. When a suitably low speed is reached, the thumb screw 123 is dis-

connected and the threads are unthreaded from the device 20 threaded up to the device 14-19, and broken beyond the rollers 23, 24, so that they collect on the roller 23. When this has been done the steam is turned off at the valve 88 so that the threads 1 are no longer softened by steam in the chamber 9. Since the threads are still being stretched the turning off of the steam increases the tension in them and this rotates the bar 16 against the action of the spring 18 and causes the guide pulley 18 to lead the threads from the roller 23 down to the small part of the conical roller 21. A condition of no stretch is thereby reached and the apparatus may be stopped altogether.

In Figure 6 is shown a form of apparatus similar to that of Figure 1, in which the tension-sensitive device shown in Figures 3, 4 and 5 is employed for other purposes in addition to those described with reference to Figures 1 and 2. In this figure, in addition to the tension-sensitive device 20 there is provided a similar device 130 in substitution for the mechanism 14 to 22 of Figure 1 and a further device 131 of the same kind for controlling the rate of rotation of the take-up bobbins 31.

The device 130 engages the threads 1 as they leave the device 20 and controls a valve 132 in a branch of the pipe 112 coming from the reducing valve 116. Air passing through the valve 132 is led by the pipe 133 to a device indicated generally at 134 and similar in form to that shown in Figure 5. The rod 135 of the device 134 is connected to a crank pin 136 on a large pinion 137. The pinion 137 engages with a small pinion 138 secured to a further large pinion 139, and the second large pinion 139 engages with a pinion 140 on the control shaft 141 of a P. I. V. gear 142. The output shaft 143 of the P. I. V. gear 142 drives the rollers 23, 24 through a chain 144.

In employing the means described above in place of the means 14 to 22 described with reference to Figure 1, the threads are led through the apparatus from the creel 3 to the lower stretching roller 23 and the P. I. V. gear 142 is set to impart to the rollers 23, 24 a speed equal to that of the rollers 8, another P. I. V. gear (not shown) constituting a common drive to the P. I. V. gear 142 and the rollers 8. The threads proceeding from the orifices 11 in the stretching chamber 9 pass as a sheet to the rollers 23, 24 and, on their way, engage with the tension-sensitive device 130. When the threads are thus being drawn through the chamber 9 without stretch, steam is turned on and threads passing through the chamber 9 are thereby softened. The softening of the threads reduces the tension therein and permits the tension-sensitive device 130 to rotate in a clockwise direction. This opens the valve 132, inflates the device 134 and rotates the shaft 141 through the rod 135 and the gears 137, 138, 139, 140. By these means the rollers 23, 24 are driven at an increasing rate until the full degree of stretch is reached. At this stage the threads 1 may be led over the roller 24 and through the rest of the device to the take-up bobbins 31, and the whole operation is then speeded up by means of the common variable speed drive to the rollers 8 and the P. I. V. gear 142.

The device 131, unlike the devices 20 and 130, acts throughout the stretching operation, its purpose being to control the speed of the take-up packages 31 so as to compensate for their increase in diameter during the winding operation. For this purpose, the whole take-up device is

driven by a variable speed electric motor 146, the motor 146 being provided with a suitable controlling resistance 147. The position of the control 148 of the resistance 147 is determined by the actuating rod 149 of a fluid pressure relay 150 controlled by the tension-sensitive device 131 which engages the threads leaving the drying drums 26. In this way, as the diameter of the packages 31 increases, they are not allowed to draw the threads at an increased rate or at a substantially higher tension, since a very slight rise of tension reduces the rate of rotation of the packages 31 and the rate of travel of the threads is kept substantially constant. The relay 150 is connected through the valve 151 (directly controlled by the device 131) in the branch of the pipe 112.

The provision of separate tension devices 20, 130, 131 is necessary, not only because of their different positions, but also because the ranges of tension with which they have to deal are different. Thus, the device 130, which is first employed in starting up, has to deal with threads in the unsoftened state, in which they are capable of exerting together a very substantial tension, and also in the fully softened state in which the tension in them is very low. The device 20 has to deal only with threads in the softened state and is concerned with a much smaller range of variation of tension than the device 130. The device 131, on the other hand, deals only with threads in the unsoftened state, the threads having been hardened in passing round the drying drums 26. Consequently, the device 131, like the device 20, is concerned with only a small range of tensions, but the tensions are generally higher than those with which the device 20 is concerned.

Having described our invention, what we desire to secure by Letters Patent is:

1. In the stretching of textile materials in the form of filaments or threads while they are running through a gaseous softening medium under pressure, running the material through the softening medium with an output-input speed ratio equal to the degree of stretch required, and then varying both the input and the output speeds while maintaining said ratio substantially constant, and simultaneously varying the pressure of the softening medium under the control of the tension in the material as it leaves said softening medium so that, as said tension varies with the change in speed, the softening effect of said medium is varied in a corresponding manner.

2. In the stretching of textile materials in the form of filaments or threads while they are running through a gaseous softening medium under pressure, running the material through the softening medium with an output-input speed ratio equal to the degree of stretch required, the full degree of stretch being effected at first at a low speed, and then increasing both the input and output speeds while maintaining said ratio substantially constant and simultaneously varying the pressure of the softening medium under the control of the tension in the material as it leaves said softening medium so that, as said tension increases with the change in speed, the softening effect of said medium is increased in a corresponding manner.

3. In the stretching of textile materials in the form of filaments or threads while they are running through a gaseous softening medium under pressure, running the material through the soft-

tening medium with an output-input speed ratio equal to the degree of stretch required, bringing the stretching operation to an end by reducing both the input and output speeds while maintaining said ratio substantially constant, and simultaneously varying the pressure of the softening medium under the control of the tension in the material as it leaves said softening medium so that, as said tension is reduced with the change in speed, the softening effect of said medium is reduced in a corresponding manner.

4. In the stretching of textile materials in the form of filaments or threads while they are running through a gaseous softening medium under pressure, controlling the pressure of the softening medium in accordance with the tension in the material as it leaves said softening medium, causing the material as it leaves the softening medium to turn through an angle whereby the tension in the material exerts a force at the point at which the material turns, amplifying said force by means of a relay, and employing the amplified force to determine the pressure of the softening medium, so that, as said tension varies with the change in speed, the softening effect of said medium is varied in a corresponding manner.

5. In the stretching of textile materials in the form of filaments or threads while they are running through a gaseous softening medium under pressure, drawing the material under tension out of said softening medium during the initial application thereof to the material, employing the tension in the material as it leaves said softening medium to control the rate of said drawing, and to increase said rate up to desired limit as said tension falls in consequence of the increasing softening influence of said medium during its initial application, thereafter increasing both the input and output speeds while maintaining substantially constant the output-input speed ratio to which the material has been brought, and then placing the pressure of the softening medium under the control of the tension in the material as it leaves said softening medium, so that, as the tension of the fully stretched material increases with the change of speed the softening effect of said medium is increased in a corresponding manner.

6. In the stretching of textile materials in the form of filaments or threads while they are running through a gaseous softening medium under pressure, running the material through the softening medium with an output-input speed ratio equal to the degree of stretch required, then reducing both the input and output speeds, while maintaining said ratio substantially constant, simultaneously placing the pressure of the softening medium under the control of the tension of the material as it leaves said softening medium, so that as said tension is reduced with the change in speed, the softening effect of said medium is reduced in a corresponding manner, and thereafter placing the speed at which the material leaves the softening medium under the control of the tension in the material as it leaves said softening medium, and cutting off the supply of softening medium to the material, whereby said speed is diminished as said tension falls in consequence of the decreasing softening influence of said medium as its supply is cut off.

7. In the stretching of textile materials in the form of filaments or threads in which the material is drawn under tension from a feed chamber into and through a stretching chamber containing a gaseous softening medium under pressure,

controlling the pressure in said feed chamber in accordance with the pressure of said softening medium, whereby the softening medium is maintained at a pressure higher than the pressure in the feed chamber by a constant amount, running the material through the softening medium with an output-input speed ratio equal to the degree of stretch required, and then varying both the input and the output speeds, while maintaining said ratio substantially constant, and simultaneously varying the pressure of the softening medium under the control of the tension in the material as it leaves said softening medium, so that, as said tension varies with the change in speed, the softening effect of said medium is varied in a corresponding manner.

8. Apparatus for stretching textile materials in the form of filaments or threads while they are running through a gaseous softening medium under pressure, said apparatus comprising a stretching chamber, means for supplying a gaseous softening medium under pressure to said stretching chamber, variable speed means for drawing the material through said chamber with an output-input speed ratio equal to the degree of stretch required, and tension-sensitive means adapted to be engaged by the material as it leaves said stretching chamber and to control the pressure of the said softening medium in said chamber, causing said pressure to vary with the tension in the material engaging with said tension-sensitive means.

9. Apparatus according to claim 8 comprising an adjustable controller for regulating the admission of softening medium to the stretching chamber so as to maintain a determined but correspondingly adjustable pressure in said chamber, the adjustment of said controller being effected by the tension-sensitive means.

10. Apparatus according to claim 8 comprising a relay for amplifying the force applied by the tension in the material to the tension-sensitive means, in order to effect control of the pressure in the stretching chamber.

11. Apparatus according to claim 8 comprising a member loaded in one direction and adapted to be urged in the opposite direction by the tension in the material, a valve for a supply of compressed air, said valve being regulated by the motion of said member, and a diaphragm exposed on one side to compressed air supplied through said valve, said diaphragm being capable of exerting a force varying with but greater than the force applied to said member.

12. Apparatus according to claim 8 comprising means for bringing the output-input speed ratio of the material passing through the stretching chamber to equality with the degree of stretch required, said means being caused to

function by the tension in the material being stretched.

13. Apparatus according to claim 8 comprising a feed chamber preceding the stretching chamber and means for controlling the pressure in said feed chamber in accordance with the pressure in said stretching chamber, said controlling means including a tension-sensitive device operated by the tension in the material being stretched.

10 14. Apparatus for stretching textile materials in the form of filaments or threads while they are running through a softening medium, said apparatus comprising a stretching chamber, means for supplying a softening medium to said stretching chamber, a rotatable drawing member adapted to draw the material after it has left said chamber, a tension-sensitive device in the neighborhood of said member adapted to deflect the material through an angle and to move under variations in the tension in the deflected material, a relay actuated by the motion of said device, and variable speed driving means for said member under the control of said relay, adapted on variation of the tension in the material to vary the speed of rotation of said member in such a sense as to counteract said variations.

15 15. Apparatus according to claim 14 comprising, as the relay, a valve actuated by the movable device and adapted to control a flow of fluid under pressure, a leak permitting the escape against a resistance of fluid passing through said valve, and a movable member having a substantial surface exposed to the pressure of said fluid behind said leak, the movement of said member controlling the variable speed driving means.

20 16. Apparatus according to claim 14 comprising a valve for varying the resistance offered by the leak to the escape of fluid, said valve being coupled with the valve actuated by the movable device in such a manner as to increase said resistance as the latter valve is opened.

25 17. Apparatus according to claim 14 wherein the rotatable drawing member is a stretching roller for drawing the material from the stretching chamber, and wherein the tension-sensitive device causes the speed of said roller to increase or decrease for the starting or stopping of the stretching operation.

30 18. Apparatus according to claim 14 wherein the rotatable drawing member is a winding spindle for the winding of the stretched material, and wherein the tension sensitive device causes the speed of said spindle to decrease as the material is wound, so that the material is wound at substantially constant tension.
